DESIGN.

—o—

F. MANKEY.

MOLDING.

No. 16,456.

Patented Jan. 12, 1886.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 16,456, dated January 12, 1886.
Application filed November 2, 1885. Serial No. 181,714. Term of patent 7 years.

To all whom it may concern:

Be it known that I, FREDERICK MANKEY, of Williamsport, Lycoming county, Pennsylvania, have invented and produced a new and original Design for Moldings, of which the following is a specification, reference being had to the accompanying photograph, forming part hereof.

Extending along the surface of the molding is 10 a raised band, A. The outlines of the opposite edges of said band are similar, and show a straight portion, B, and curved portion C, the said portions alternating. The curved portions C are longer than the straight portions B, and the curved portions C on one edge are disposed opposite to the straight portions B 15 on the other edge.

Upon the surface of the raised band A ap-

pear inclined scores or channels D, which extend from the extremities of each straight portion B on one edge to the extremities of the opposite curved portion C on the other edge.

The general appearance of the design resembles that of a series of keystones with 25 rounded tops, every other one being reversed.

I claim—

The design for a molding herein shown and described, which consists in the raised band A, having at its edges alternate straight portions B and curved portions C, and on its surface channels D.

FREDERICK MANKEY.
